UNITED STATES PATENT OFFICE.

ARNOLD STUCKI, OF PITTSBURGH, PENNSYLVANIA.

ROLLER SIDE BEARING.

1,082,179.

Specification of Letters Patent. Patented Dec. 23, 1913.

Application filed February 14, 1912. Serial No. 677,536.

To all whom it may concern:

Be it known that I, ARNOLD STUCKI, a resident of Pittsburgh, in the county of Allegheny and State of Pennsylvania, have invented a new and useful Improvement in Roller Side Bearings, of which the following is a specification.

This invention relates to roller side bearings for railway trucks, and is particularly adapted to those forms of railway trucks in which the car body is supported solely on the side bearings, such as one form of street railway trucks now in use.

The object of the invention is to provide a side bearing for the character of trucks stated which completely overcomes the tremendous friction which occurs when the car passes around curves.

Another object is to provide for a long travel of the roller without interfering with existing conditions, so as to permit the trucks to swivel on the car body through a sharp arc, which can be applied to existing as well as to new cars, and which serves to guide the truck in its swiveling motion, as well as possessing other advantages which will hereinafter appear.

In the accompanying drawings Figure 1 is a side elevation of a portion of a truck frame showing my roller bearing applied thereto; Fig. 2 is a plan view of the roller bearing; Fig. 3 is in part a side elevation and in part a vertical central longitudinal section thereof; and Fig. 4 is a central transverse section on the line 4—4, Fig. 3.

A portion of the side frame of the truck is shown at 1. This may be of any suitable or desired type. Mounted in the side frame to slide vertically therein are a pair of posts 2 and 3 which normally are held projected upwardly by means of the helical spring 4 surrounding the same. The tops of the posts are rounded and fit into pockets 5 in a cap 6, the cap being held in place on the posts by pins 7. This is a type of motor truck used in considerable numbers on different street car lines in various cities of the United States. As used the cap on top of the spring post is a solid casting provided with wearing shoes which can be removed. The car body rests directly upon these caps

and is entirely supported thereby. These solid caps slide upon and are guided by arc shaped angle guide members secured to the bottom of the car body. The caps and guides are located a long distance from the center of oscillation, and the friction between the caps and guides, working on such a long arm, is tremendous, so that it requires great force to swivel the truck under the car. This force is transmitted to the wheel flanges and rail head, producing a grinding action which quickly wears both to such an extent that the power wasted in swiveling the truck on curves is probably the least item of loss. The difficulty of swiveling the truck also tends to derailment of the car.

With my invention the cap 6 is so constructed as to provide a housing for a freely traveling roller. As shown in the drawings, the cap and housing are a single integral casting, but the number of parts and the character of material from which the same is made is not of the essence of the invention. As shown, the housing has the upwardly projecting side walls 8 and end walls 9 forming substantially a box. The bottom of the housing is provided on each side with runways 10 and intermediate the same with a depressed portion 11. Preferably the runways are formed of hardened steel plates 12 secured to the bottom of the housing by countersunk rivets 13 or other suitable fastening means. In the housing is a freely traveling roller comprising the large central portion 15 adapted to have the car body rest directly thereupon and supporting said car body, and the reduced end portions 16 which freely roll on the runways 10. The central depressed portion 11 is of such depth that the larger portion 15 of the roller does not contact therewith. The car body on its bottom carries a suitable bearing plate or member 17 resting upon the roller 15.

Preferably the housing and the runways 10 are of arc shape, being formed on a circle struck from the theoretical center of rotation or swiveling of the truck under the car body, and the roller 15 and its reduced end portions 16 are all conical, the lines of these cones converging at the theoretical center of

oscillation of the truck. One of the runways 10 is higher than the other, and both runways are inclined laterally to such a degree that the upper longitudinal surface of the roller 15 is horizontal, as shown in Fig. 3. As a consequence, the roller tends to run in an arc shaped path and therefore guides the swiveling motion of the truck so that the bearing plates 17 could be ordinary flat plates, were it not for abnormal and accidental heavy lateral forces induced by abnormal rail and speed conditions. Even if of angle shape the side bearings do not normally bear against the depending flange, thereby removing absolutely this element of friction so pronounced with the old solid spring caps. This is due to the tendency of the rollers naturally to run in an arc shaped path. The outer wall of the housing is on a curve conforming to the arc of the member 17 so that if the housing is forced against the depending flange, it has a long bearing thereagainst.

The particular form of rollers, that is, with an enlarged part to carry the car body and with parts of smaller diameter for running on the runway, is particularly adapted to the form of truck in which the distance between the spring posts 2 and 3 is limited, as it is not advisable to have the roller roll directly over either spring post, or too closely thereto, which would have a tendency for the other spring post to fly up and throw the bearing out of level. The reduced end portions 16 of the rollers give to the latter a very considerable number of revolutions without bringing them too close over the spring post, while the enlarged central portion 15 allows of a longer travel of the car body, due to its greater diameter, thereby giving the large travel required in order to permit of a large angular variation of the truck under the car body, such as is caused when passing around sharp curves, and without coming too close to one spring post or the other.

The roller is entirely free to travel in the housing, but is limited by the vertical end wall 9 thereof which serve as stops. The walls of the housing are sufficiently deep to prevent the roller from becoming accidentally displaced.

Any dirt or water getting into the housing escapes through the central opening 19, or through side openings 20 which are formed by cutting away a part of the bottom to provide spaces for the heads of the rivets 13.

The arc shaped runway is not symmetrical relative to the line connecting the points of attachment of the posts 2 and 3, as appears clearly in Fig. 2. This is due to the fact that with this type of truck, the theoretical center of oscillation is some distance

from a straight line connecting the two side bearings or supports. The housing described forms the cap for the spring posts 1 and 2 as well as forming the runway for the roller 15. It is designed to fit existing trucks of the type described having spring posts to which are connected caps forming the sole support for the car body, the car having no center bearing. This side bearing is absolutely frictionless, as the roller is free to travel back and forth in the housing. Said roller cannot become displaced because the load is always resting thereupon. The roller also serves to guide the truck in its swiveling movement, as there is no slipping or sliding necessary between the car body and the roller or the roller and the bearing, due to the tendency of the roller to always travel in an arc shaped path. It therefore eliminates the friction of the old form of solid bearing caps for the spring posts, the grinding and wear due to such sliding movements, the waste of power, the grinding and wear of the wheel flanges and rails, and the liability of derailment of the old form of spring caps.

What I claim is:

1. The combination with a truck frame, of spring posts mounted therein, a cap mounted on said spring posts and arranged to form runways having portions at different heights and provided with end walls forming stops, and a roller having two diameters, the smaller diameter arranged to roll on said runways and the larger diameter arranged to have the car body rest thereupon and to contact said end walls at the limits of movement of said roller in both directions.

2. The combination with a truck frame, of spring posts mounted therein, a cap for said spring posts provided with an open top and with a central depressed portion and with runways at the sides of said central depressed portion, and a roller having an enlarged central portion projecting down into the depressed portion and adapted to have the car body rest thereupon and having reduced end portions rolling on said runways, said roller resting loosely upon said runways and being removable from the open top of said cap when the car body is removed therefrom.

3. The combination with a truck frame, of spring posts mounted therein, a cap mounted on said spring posts and providing arc shaped runways, and a conical roller arranged to travel on said runways and adapted to have the car body rest thereupon and forming a guide and a support for the car body, said runways being inclined laterally to a degree that the upper longitudinal surface of the roller is horizontal.

4. A truck side bearing comprising a

housing having its bottom forming an arc shaped runway, and a conical roller arranged to travel on said runway and adapted to have the car body rest thereupon, said runway being inclined laterally to a degree that the upper longitudinal surface of the roller is horizontal.

In testimony whereof, I have hereunto set my hand.

ARNOLD STUCKI.
